CHAIR HEIGHT ADJUSTMENT MEANS
Stanley J. Nocek, Northlake, and George H. Stell, Elmhurst, Ill., assignors to Precision Metal Workers, Chicago, Ill., a co-partnership composed of Ralph Robinson and K. O. Robinson

Filed Jan. 22, 1963, Ser. No. 253,137
3 Claims. (Cl. 248—405)

This invention relates to chair height adjustment devices and methods and particularly to improvements in chair height adjustment devices to be used in office swivel chairs.

Office swivel chairs presently available and used are almost always provided with height adjustment devices so that a given chair may be easily and rapidly adjusted to a height most comfortable for the intended user. A very widely used height adjustment device embodies a rotatable handwheel mounted to be moved upwardly and downwardly along a threaded shaft upon which the chair body is supported. Such handwheels have consisted of several members which it has been necessary to fabricate separately and then combine into a single unitary member, such as by welding or riveting, to enable the handwheel to move along the threaded shaft.

It is a primary object of this invention to provide a chair having a simpler and more economical chair height adjustment mechanism than has heretofore been available.

Another object of this invention is the provision in a chair having a chair body and a pedestal, of a unitary handwheel in combination with a handwheel type chair height adjustment mechanism which handwheel may be formed from a single flat sheet, such as steel, which handwheel has a single thread and is adapted to move along a threaded shaft to lower and to raise the chair body with respect to the pedestal.

A further object of this invention is the provision of a simple, novel chair height adjustment mechanism having an integral handwheel formed from a single sheet of metal and novel recessed bearing means, in which the handwheel has a single thread and is adapted to engage a threaded shaft directly to move a chair body upwardly and downwardly along that threaded shaft with respect to a chair pedestal.

Yet another object of this invention is to provide a novel method of forming a unitary handwheel for use in a chair height adjustment mechanism comprising removing a circular segment centrally of a piece of planar sheet material having a planar upper surface and a planar lower surface, swaging the spaced parallel edges of said opening to form spaced converging edges terminating in a common cylindrical edge, all of said edges lying between said upper surface and said lower surface, trimming and slotting said edges, and displacing said edges with respect to said planar sheet material so that said edges lie along a common helical path and so that at least a portion of said edges lie outside the planes defined by said upper and lower surfaces.

Still other objects and advantages of this invention will become apparent from the following description and drawings of which:

FIG. 1 illustrates an office swivel chair of the type with which a height adjustment device of this invention may be used;

FIG. 2 is an enlarged side elevation, partially in section, of a height adjustment device of this invention;

FIG. 3 is a partial side section showing the bearing and handwheel in their interlocked relationship;

FIG. 4 is a partial side elevation, similar to FIG. 3;

FIG. 5 is an enlarged partial sectional view taken sub-

2

stantially along line 5—5 of FIG. 6, showing the handwheel thread;

FIG. 6 is a bottom view of the handwheel of FIG. 2;

FIG. 7 is a partial sectional view of the handwheel thread of FIG. 6, taken substantially along line 7—7 of FIG. 6; and

FIG. 8 is a plan view, partially in section, of the bearing of FIG. 2.

The height adjustment mechanism 10 useful with the chair C of FIG. 1 is shown as being located below a chair body 12 and above a chair pedestal 14 which is rollingly supported upon a floor F by casters 16.

A presently preferred embodiment of the height adjustment mechanism 10 of this invention, as best seen in FIG. 2, includes a threaded shaft 18 having a generally helical thread 20 and a keyway 22 which extends to the root of thread 20. At its upper end shaft 18 is fixedly connected to a chair body supporting mechanism 23 (FIG. 1) upon which the chair body 12 is balanced. The chair body supporting mechanism is constructed to permit the chair body 12 to rock with respect to the pedestal 14.

Adjacent the chair pedestal 14, height adjustment mechanism 10 is provided with a pedestal hub 24. Hub 24 rests upon the pedestal. It includes an annular circular planar section 25 and an upstanding cylindrical sleeve portion 26. Cylindrical sleeve portion 26 is concentric with a bore 28 in pedestal 14. The annular circular planar section 25 of hub 24 rests upon central portions of chair pedestal 14 to assist in stabilizing the height adjustment mechanism 10 and the chair body 12. It may be connected to chair pedestal 14 by means such as screws (not shown).

Extending upwardly from hub 24 and lying within sleeve portion 26 is a shaft housing 30. Shaft housing 30 includes a cylindrical segment 32 and an upper flange segment 34. Flange segment 34 is adapted to rest upon the upper end of hub sleeve portion 26. Housing cylindrical segment 32 is very slightly larger than the thread diameter of shaft 18 and is adapted, therefore, to guidingly and slidably receive shaft 18. Shaft housing 30 and hub 24 may be locked to each other by a set screw 36 received in suitable threaded openings provided in hub sleeve 26 and housing segment 32. It is therefore apparent that hub 24 and housing 30 form an integral unit 40 which serves to balance chair body 12 upon pedestal 14. They also cooperate to line pedestal bore 28 so that it reciprocally receives and guides shaft 18 thereby preventing wobbling and inducing stability in the height adjustment mechanism 10, hence stability of the chair body 12 with respect to pedestal 14.

Overlying the pedestal hub 24 is a novel handwheel 40 constructed in accordance with this invention. As is apparent, handwheel 40 is adapted to rotate about shaft 18 and to be moved therewith to reciprocate chair body 12 and to cause it to be elevated and lowered. A flange 42, welded to the bottom of handwheel 40, has a downwardly extending arm 44 which is provided with a tapped opening in which is located a complementary threaded bolt 46. Bolt 46 is positioned so that it may underlie circular flange segment 34 of housing 30 thereby limiting the freedom of vertical movement of handwheel 40 with respect to pedestal 14, however permitting handwheel 40 to rotate relatively freely with respect to pedestal 14. Bolt 46 may be unscrewed so that the chair body and associated shaft may be removed from the pedestal. Access to bolt 46 is provided by an opening 47 in the handwheel flange.

An annular bearing 48, coaxial with shaft 18, lies between the upper surface of housing flange segment 34 and the lower surface of handwheel 40. Bearing 48 is of molded nylon. It includes a central annular web portion 50 and an outer flange 52. Flange 52 on both its upper

and lower surface bears a plurality of equidistantly spaced dimples 54. On the inner surface of web portion 50, bearing 48 bears a key 56 which is proportioned to ride in shaft keyway 22 thereby preventing relative rotational movement between shaft 18 and bearing 48.

As best seen in FIGS. 3 and 4, dimples 54 on the lower face of bearing 48, bear against the flat upper surface 58 of housing flange segment 34. The dimples and the upper surface 58 serve as the principal bearing means upon which chair body 12 rotates with respect to pedestal 14.

Handwheel 40, as may be appreciated from the accompanying descriptive drawings, is formed from a single piece of flat sheet stock of suitable thickness. As best seen in FIGS. 2 and 6, handwheel 40 includes a generally circular central body portion 60 and a flange 62 disposed substantially normally to the body portion 60 around its entire periphery. A plurality of elongated flange detents 64 are provided in flange 62 to reinforce handwheel 40 and to facilitate gripping and rotating handwheel 40 to change the height of chair body 12.

At its center, handwheel 40 is provided with a mating thread for shaft thread 20. In accordance with this invention, handwheel thread 70 is integral at its root 71 with and is formed from the same sheet from which handwheel 40 itself is formed. The thread is formed so that its pitch is the same as the pitch of shaft thread 20 with which it cooperates. Since thread 70 is formed integrally with handwheel 40, it defines but one substantially complete helix as is best seen in FIGS. 5, 6 and 7. FIGURE 5 shows the terminal ends 72 of thread 70. And as seen in FIG. 6, except at the very ends 72 of thread 70, the apex 73 of thread 70 defines a circular opening centrally of the central body portion 60.

As is discernible in FIG. 2, shaft thread 20 is an Acme thread, trapezoidal in cross-section. That configuration provides inclined bearing surfaces, upper bearing surface 74 and lower bearing surface 76, which cooperate with complementary inclined upper bearing surface 78 and lower bearing surface 80 of handwheel thread 70, similarly an Acme thread, to facilitate and make easier rotation of the handwheel with respect to the shaft. As is also discernible from FIG. 2, the handwheel thread apex 73 terminates inwardly of shaft thread 20 very closely adjacent its root.

Handwheel 40, in its central body portion 60, includes a plurality of generally elongated radially disposed depressions 82. Depressions 82 which strengthen central body portion 60 are spaced to mate with dimples 54 on the upper surface of bearing 48 in the manner shown in FIGS. 3 and 4. It is the tendency of dimples 54 to fall into depressions 82 as chair body 12 is rotated. However the depressions are not so deep that handwheel 40 is prevented from rotating, which, because bearing 48 is keyed to shaft 18, requires dimples 54 to disengage from depressions 82 rather easily. Thus it is that bearing 48 is releasably locked to handwheel. And when chair body 12 is rotated, because it is fixed to shaft 18 and because shaft 18 is keyed to bearing 48 and bearing 48 is "locked" to handwheel 40, handwheel 40 will not rotate with respect to shaft 18 and will not accidentally change the height of chair body 12.

The handwheel 40, as has been stated, is formed from a single sheet of flat planar material. It is fabricated by first removing a circular segment and forming the body portion and flange 62 with the associated depressions and detents. The Acme thread is then formed by placing the handwheel blank in a swaging die and by forcing two male punch members against the upper and lower edges of the opening to form the taper characteristic of the Acme thread. Those edges continue to lie between the upper and lower surfaces of the central body portion and define a common cylindrical edge vertically disposed with respect to the upper and lower surfaces of the central body portion. Next the inside edge of the thread is trimmed to the proper diameter and a slot which will define the ends 72 of the threads is cut in the thread to facilitate

that operation which will give the proper pitch to the thread.

All of that is done while the thread lies in the plane of the body portion. Finally, the thread is brought to that pitch which will enable it to cooperate with a helical shaft thread by operating upon it in a forming die.

Thus it is that the thread is formed so that the edges lie along a common helical path and so that at least a portion of the edges lie outside of the planes of the upper and lower surfaces of the central body portion. With the thread formed, the handwheel is ready for use.

In operation, as handwheel 40 is rotated, it is driven along shaft 18 by virtue of the cooperation between threads 20 and 70. Where bearing surfaces, such as upper inclined surface 78 of the handwheel thread 70 and the lower inclined surface 74 of shaft thread 20 are provided, the rotation of handwheel 40 is made easier. The single helical thread 70 of handwheel 40 also facilitates easier rotation than do the plurality of threads normally and conventionally used in association with handwheel assemblies. Even when tested under loads of as much as 3600 pounds, the handwheel having but a single integral helical thread was found to resist distortion completely, demonstrating its completely satisfactory functioning in chair height adjustment mechanisms.

The single thread 70 has been shown as extending above and below the plane of the central body portion 60 of handwheel 40. In fact, about 180° of the thread extends upwardly from, and about 180° of the thread extends downwardly from, the central plane of the central body portion, and the ends of the thread are substantially equidistantly spaced from the opposite faces of central body portion 60. It is apparent that the single thread may be struck out upwardly or downwardly of the central body portion, if desired.

Because thread 70 extends downwardly below the lower face of central body portion 60, bearing 48 must be proportioned to receive thread 70 if it is to lie against the lower face of the handwheel central body portion 60 and if dimples 54 are to mate with depressions 82. Therefore, the outer diameter d (FIG. 8) of central annular web 50 of bearing 48 is greater than the outer diameter of thread 70. So also is the vertical dimension h (FIG. 2) greater than the vertical extent of that portion of thread 70 which extends below central body portion 60. Therefore thread 70 clears both the annular web 50 and outer flange 52 of bearing 48, the recess of which is both deep enough and wide enough to accommodate thread 70. In that respect see FIG. 3 particularly.

Although the single thread 70 has been shown as having one end lying above the plane of central body portion 60 and its other end lying below the plane of central body portion 60, it is apparent that as long as the pitch of the single thread is the same as the pitch of the shaft thread the handwheel will operate satisfactorily.

The novel height adjustment mechanism is simple to fabricate and to operate. The handwheel, particularly, and its associated novel bearing means in the environment of chair height adjustment mechanisms, cooperate to provide a desirable improvement in office chairs.

That minor modifications and changes may be made in the embodiment illustrated and described without departing from the spirit and scope of this invention will become apparent to those of ordinary skill in the art from the foregoing description and drawings of one presently preferred embodiment of our invention. For that reason, we do not intend this invention to be limited except as may be necessary in view of the following claims.

We claim:

1. In a chair having a chair body, the height of which is adjustable, the combination comprising a chair pedestal and a chair body rotatable with respect thereto, a shaft having a continuous helical thread integral therewith, means mounting said chair body upon one end of said shaft, means connected to said chair pedestal for mounting said shaft upon said pedestal at a point remote from said

one end of said shaft, a handwheel including a central body portion, said central body portion defining a single integral helical thread of a pitch equal to the pitch of the thread of said shaft, said handwheel thread defining an opening in said central body portion and engaging said shaft thread at a point intermediate said pedestal and said chair body for reciprocating said shaft with respect to said pedestal, said handwheel thread extending below the central body portion, a bearing coaxial with said shaft intermediate said pedestal and said handwheel having a diameter greater than said handwheel thread, said bearing defining a cylindrical recess deep enough and wide enough to contain the portion of said handwheel thread extending below the central body portion without contacting said thread, means non-rotatably keying said bearing to said shaft, and means releasably locking said bearing to said handwheel, whereby as said handwheel is rotated on said shaft, said shaft reciprocates with respect to said pedestal thereby adjusting the height of the chair body, and as said chair body is rotated with respect to said pedestal, the height of said chair body remains unchanged.

2. In a chair having height adjustment means, the improvement comprising a handwheel formed from a single continuous piece of sheet material, said handwheel having a substantially flat central body portion, said central body portion including a single helical thread integral at its root therewith, the apex of said thread defining a substantially circular opening adjacent the center of said central body portion, said thread extending below the plane of said central body portion, and a recessed bearing having a central bore concentric with said opening surrounding, but not contacting, said thread, said bearing further contacting said central body portion adjacent said thread, and cooperating means on said central body portion and said bearing for releasably locking said bearing to said central body portion.

3. In a chair having a chair pedestal, a chair body rotatable with respect to said chair pedestal, and means supported by said chair pedestal for changing the height of the chair body with respect to the chair pedestal, height adjustment mechanism including a shaft upon which said

chair body is supported and a helical thread integral with said shaft; a handwheel formed from a single continuous piece of sheet material threadedly engaging said threaded shaft; said handwheel including a body portion defining adjacent its center a single helical thread integral at its root with said body portion, the apex of said thread circumscribing a substantially complete circular opening in said body portion, said handwheel thread being of a pitch the same as the pitch of the shaft thread, and a vertical bore in said chair pedestal and surrounding at least a portion of said shaft, whereby when said handwheel is rotated, said threaded shaft is reciprocated with respect to said pedestal to adjust the height of said chair body, the chair being further characterized by one end of said handwheel thread lying below the handwheel body portion and 10 wherein said handwheel thread has an inclined upper bearing surface and said shaft thread includes a complementary inclined lower bearing surface to facilitate rotating said handwheel, and further including a recessed bearing, co-axial with said shaft, underlying said handwheel body portion and surrounding, but not contacting, said handwheel thread, and cooperating means on said bearing and said body portion for releasably locking said bearing and said body portion to each other.
